UNITED STATES PATENT OFFICE.

BURT F. UPHAM, OF BROOKLINE, AND FRANK R. BELLUCHE, OF MANSFIELD, MASSACHUSETTS, ASSIGNORS TO UNITED PRINTING MACHINERY COMPANY, OF BOSTON, MASSACHUSETTS, A CORPORATION OF MASSACHUSETTS.

BED-MOTION FOR SHEET-PRINTING PRESSES.

1,398,817.

Specification of Letters Patent. Patented Nov. 29, 1921.

Application filed March 17, 1920. Serial No. 366,592.

To all whom it may concern:

Be it known that we, BURT F. UPHAM and FRANK R. BELLUCHE, citizens of the United States, said UPHAM residing at Brookline, in the county of Norfolk and State of Massachusetts, and said BELLUCHE residing at Mansfield, in the county of Bristol and State of Massachusetts, have invented certain new and useful Improvements in Bed-Motions for Sheet-Printing Presses, and we hereby declare that the following is a full, clear, and exact description thereof, reference being had to the accompanying drawings, which form part of this specification.

15 This invention is a novel means for imparting reciprocatory movements to objects, such, for example, as the beds of printing presses, where it is desired to move the object at a uniform speed during one portion of 20 each stroke and to reverse the movement of the object gradually at the end of such uniform movement.

The invention in particular is an improvement upon the movement shown in Burt F. 25 UPHAM's Patent No. 1,094,405 of April 21, 1914; and the objects of the present invention are, to provide novel means for driving the bed on the uniform portions of its strokes; to provide novel means for reversing 30 the bed at the end of the uniform portions of its strokes; to so construct the reversing mechanism that the reverse stresses will be exerted on the bed at approximately its center; to make the reversing mechanism 35 compact, durable, and easily accessible; to simplify and improve the construction of the reversing mechanism shown in said patent; and to dispense with the swingable parts or gates in the reversing mechanism.

40 In this invention as in said patent the mechanism is so constructed that during the reversals, the forces acting on the reciprocating bed and tending to stop and start the same in the opposite direction will be exerted 45 in a downward direction on the bed and parallel thereto, and thus tend to keep it at all times in close contact with the bed supports, and prevent any tendency to throw the bed upwardly away from the supports 50 during the reversing operation.

We will explain the invention with reference to the accompanying drawings which

illustrate one practical embodiment thereof, adapted for reciprocating the bed of a printing press, or like machine to enable others 55 skilled in the art to understand and use the invention; but the invention is not restricted to the particular construction and application of the invention shown in said drawings, and all changes, variations and modifications are intended to be included as fall within the scope of the claims appended hereto.

In said drawings:

Figure 1 is a longitudinal sectional elevation on line 1—1 of Fig. 3 of part of a printing press showing the means for driving and reversing the bed.

Fig. 2 is a similar view looking from the opposite side on line 2—2 of Fig. 3.

Fig. 3 is a right hand elevation of Fig. 1.

Fig. 4 is a transverse vertical section on line 4—4, of Fig. 1.

Fig. 5 is a detail edge view of one of the reversing gears and its rollers.

Fig. 6 is a diagrammatic detail view of the reversing mechanism.

Fig. 7 is a detail view showing the gear shifting yoke in side elevation, and some immediately related parts.

Fig. 8 is a detail plan view of the reversing and bed driving gearing.

The bed 1 of the press, as shown in Fig. 2, is preferably provided on its under side with a number of transversely disposed ribs 85 1^a, and with parallel longitudinally disposed bearing portions 1^b, which rest upon the usual bed rollers or sliders 2^a. The portions 1^b may be prolonged at each end of the bed by means of extensions 1^c formed integral 90 with the bed as shown. The sliders 2^a are shown as supported on the usual guides 2 rigidly mounted in the press frames as usual. The bed is prevented from lateral play on the sliders 2^a by means of gibbs 1^f attached 95 to the under side of the bed and engaging opposite sides of the guides 2, as shown in Fig. 3.

The bed 1 is further preferably formed with an integral longitudinally depending portion 1^e, intermediate with the bearers 1^b and, in the example shown, at one side of the center of the bed. The inner portion or face 1^k of this part 1^e is preferably perpen-

dicular to the top surface of the bed and in a vertical plane approximately parallel with the central line of the bed.

In the opposite ends of the part 1^e are formed air cylinders 1^h (see Fig. 1) which are adapted to engage pistons (not shown) at opposite ends of the bed, for the purpose of air cushioning the reversal movements of the bed in the usual manner.

- 10 A bracket casting 3 (see Fig. 6) is attached to the inner face 1^k of the portion 1^e, said casting being approximately triangular in form and arranged with its apex uppermost, and preferably at the transverse center line of the bed. The sides of this casting are oppositely inclined at angles of less than ninety degrees (preferably 45 degrees each) to the surface of the bed. To the opposite inclined surfaces of this casting 3 are respectively securely attached removable shoes 3^a, 3^b, hereinafter referred to.

A guide casting 4 is bolted to the face 1^k of the part 1^e, and lies exterior to but substantially parallel with the shoe 3^a on the casting 3. The side of casting 4 opposite the shoe 3^a is slightly concaved as at 4^e and this concaved portion is adapted to be contacted by a guard roller 15^a during the period of reverse, as hereinafter explained.

30 The casting 4 is also provided near its upper end with a short straight portion 4^c, to which may be attached a short straight shoe 4^a, which lies exactly parallel with and opposite to the upper portion of the shoe 3^a (see Fig. 2) and the reverse roller 5^a (hereinafter referred to) traverses the "slot" between the opposed shoes 3^a, 4^a during the actual reversal of the bed when at the outer or feed-board end of the press.

40 A guide casting 4^m, in all respects similar to but the reverse of casting 4, is secured to the face 1^k of part 1^e directly opposite the shoe 3^b on the casting 3; this casting 4^m has a curved face 4ⁱ, similar to the curved face 4^e, of casting 4 and adapted to be engaged with a guide roller 15^b (hereinafter referred to) during the reversal of the bed at the inner end of its stroke. Casting 4^m has a straight upper portion 4ⁿ to which is secured a shoe 4^b, (corresponding to the shoe 4^a) which is directly opposite and parallel with the upper end of the shoe 3^b; and the "slot" between the shoes 3^b is traversed by the reversing roller 5^b (hereinafter referred to) during the actual reversal of the bed when at the inner end of the press.

The parts 3, 4, and 4^m are rigidly attached together and to the bed, and have no relative movement in the operation of the mechanism. They might be formed integral with each other, and with the bed, but for convenience in manufacture are formed separately and bolted together.

65 In the construction shown the "slot" being curved so that it can clear the seg-

formed between the opposed shoes 3^a, 4^a is adapted to be engaged by a roller 5^a mounted upon a crank pin 6^a attached to a gear 6 (hereinafter referred to) when the bed is moving outward and at the end of 70 the uniform portion of its stroke. The "slot" formed between the opposed shoes 3^b, 4^b is adapted to be engaged by a roller 5^b (mounted on a gear 7 corresponding to the gear 6), when the bed is moving inward 75 and at the end of the uniform part of its stroke. Two bed driving gears 8 and 9 are arranged between the gears 6 and 7 (see Figs. 1, 2 and 8.) The gears 6, 7, 8, and 9 are of the same size; gears 8 and 9 intermesh; gear 9 meshes with and drives gear 6; and gear 8 meshes with and drives gear 7; the gears 8 and 9 rotate in opposite directions, as do the gears 6 and 7. All these gears are journaled or supported in the main frame in any suitable way. The gear 9 may be mounted on a driven shaft 9^c suitably journaled in the frame and said shaft is preferably so geared to the cylinder shaft (by any suitable gears, not shown) that gear 90 9 will (in the construction shown) make, say two revolutions to each revolution of the impression cylinder C, and consequently each of the gears 6, 7, and 8 makes a like number of revolutions, to each revolution of 95 the cylinder.

In the construction shown the bed is driven uniformly during one-half a revolution of gear 9 (or 8) and at the end of such uniform movement and during the next half revolution of the gear 9 (or 8) the bed is reversed so that in the movement the time required for uniform movement of the bed and the time required for reversal of the bed are equal; and the total length of stroke of the bed (in either direction) will approximately equal the circumference of the gear 9.

In the example shown the gear 9 drives the bed during the uniform portion of its outward stroke, and the gear 8 drives the bed during the uniform portion of its inward stroke and the bed is reversed at a time when neither gear 8 or 9 is in control of the bed.

To enable the gears 8 and 9 to rotate on fixed axes and at the same time drive the bed, 115 we preferably provide shiftable intermediate gear or gears between the gears 8 and 9 and the bed rack. In the construction shown the bed carries a single rack 11, which is continuously in mesh with a pinion 10 rotatably 120 mounted on a stub shaft 10^a carried by a yoke 10^c; and on this stub-shaft 10^a and rigidly connected with gear 10 is a slightly smaller gear 10^b, which latter is caused to alternately mesh with segments 9^b and 8^b on the sides 125 of gears 9 and 8.

As shown the yoke 10^c is fulcrumed on a pin or stud 10^d suitably mounted in the frame adjacent the gears 8 and 9, said yoke 130 being curved so that it can clear the seg-

mental gears 9^b, 8^b. The yoke has a depending arm 10^e, which carries a friction roller 10^f engaging a race cam 12 mounted on a shaft 12^c which is geared to rotate once for each complete reciprocation of the bed.

The cam 12 is so shaped that during each reversal of movement of the bed and while the bed is under the control of the reversing roller 5^a (or 5^b) and the related slot, the cam will shift yoke 10^b so as to move the pinion 10 out of position to be engaged with the segment 9^b (or 8^b) and into position to be engaged with the other segment 8^b (or 9^b). The yoke is caused to shift the pinion 10^b during the reversals of the bed and while it is clear of both segments 8^b, and 9^b.

During each reversal of the bed the pinions 10, 10^b, will be slowed down, stopped, and reversed in rotation by reason of the constant engagement of the bed rack 11 with pinion 10; and as the bed is slowed down, stopped, reversed, and brought up to full speed in the opposite direction, the pinions 10, 10^b are also slowed down, stopped, reversed, and brought up to full peripheral speed equal to the speed of movement of the segments 9^b, 8^b, so that the pinion 10^b will mesh with the segment 8^b (or 9^b) without any clashing just before and as the roller 5^a (or 5^b) surrenders control of the bed at the end of the reversal movement; and thereafter the bed is positively driven on its uniform stroke by the motion positively imparted thereto by the gear 8 (or 9) through the segment 8^b (or 9^b) and the pinions 10, 10^b, and rack 11.

By referring to Fig. 2 it will be seen that the segments 9^b, 8^b, correspond in radius and size with the gears 8 and 9, and their teeth 40 are uniform with the teeth of the gears and these segments may be attached to or formed with said gears.

As shown each of the segments 8^b, 9^b, is practically 180 degrees in extent and they are 45 so set on their respective gears 8 and 9 so that the leading edges of these segments will simultaneously reach the points for engagement with the pinion 10^b; or for disengagement therefrom, at the same time.

50 The reversing roller 5^a is shown as rotatably mounted on a stud 6^a attached to gear 6, this stud being within the base line of the gear teeth and therefore said gear does not require any offset or projection to support 55 the reversing roller 5^a. The reversing roller 5^b, which is similar to roller 5^a, is similarly mounted upon the gear 7.

As shown in Fig. 1 the bed is moving to the right and has just completed the uniform 60 portion of its stroke (imparted thereto by segment 9^b meshing with pinion 10^b) and the segment 9^b is just passing out of mesh with the pinion 10^b; at the same moment the roller 5^a is just entering the slot between 65 the opposed shoes 3^a, 4^a (see Fig. 6), and

will take control of the bed and continue to move the same to the right (after segment 9^b leaves gear 10^b) while gear 6 makes one-fourth of a revolution. During this time the roller 5^a in conjunction with the slot (and 70 particularly shoe 3^a) gradually slows down the bed to a full stop; then owing to the continued orbital movement of the roller 5^a by the gear 6, said roller operating on shoe 3^a, first starts the bed rack in the reverse 75 direction and gradually accelerates the movement of the bed up to full speed by the time the gear 6 has completed a half revolution.

During the reversal movement when the bed is operating at speed the pressure contact is exerted between the roller 5^a and the shoe 3^a and the pressure is exerted with a downward component on the shoe, and while the roller 5^a is in engagement with the shoe 3^a the forces tending to stop or start the bed 80 will pull the bed downward and prevent the tendency of the bed to throw upward at the end of its stroke, or during the reverse, when the machine is in normal operation. The forces tending to stop and start the bed 90 are exerted in directions substantially at forty-five degrees to the bed.

During such reversal of the bed the pinion 10^b is out of mesh with both segments 9^b, 8^b, and 9^b, but is under control of the bed 95 rack 11, which remains in mesh with the pinion 10, and therefore said pinions 10—10^b are slowed down, stopped, and reversed in rotation in accordance with the slowing down and stoppage and reversal of the 100 movement of the bed; and said pinions are brought up to fully rotary speed (equal to the peripheral speed of the gears 8 and 9 and segments 8^b, 9^b) by the time the reversal of the bed is completed.

105 During this reversal and while pinion 10^b is clear of both segments 9^b, 8^b, cam 12 rocks the yoke so as to move the pinions 10, 10^b laterally, or edgewise, from the position in which the pinion 10^b would mesh with the 110 segment 9^b, into such position that said pinion will be meshed with the segment 8^b.

In the interval between the moment when segment 9^b runs out of mesh with pinion 10^b and the moment when the segment 8^b comes 115 into mesh with the pinion 10^b, the rotation of the pinion 10^b is reversed (as stated) and when the segment 8^b meshes with pinion 10^b to drive the same, roller 5^a leaves the shoe 3^a and the bed is driven on its backward 120 stroke by the segment 8^b meshing with the pinion 10^b and pinion 10 meshing with the bed rack 11.

Just before the end of the uniform portion of the inward stroke of the bed (that is, 125 just before the segment 8^b runs out of mesh with the pinion 10^b) the roller 5^b enters the slot between the opposed shoes 3^b, 4^b and takes control of the bed, and reverses the same during the time pinion 10^b is out of 130

mesh with both segments 8^b, 9^b; and during this reversal the direction of rotation of pinion 10^b is reversed, so that by the time the roller 5^a has reversed the bed and is ready to surrender control thereof the cam 12 has rocked the yoke 10^c to shift pinions 10, 10^b into position to enable segment 9^b to again engage pinion 10^b and drive the bed on its forward stroke at uniform speed.

- 10 As stated the reverse roller 5^a (or 5^b) engages the related slot and accomplishes the reversal thereof as above explained. To obviate the possibility of the bed moving improperly and during this reversal movement 15 after the roller 5^a, (or 5^b) has cleared the short shoe 4^a (or 4^b) we provide supplemental guard rollers 15^a, 15^b, respectively mounted on the gears 6 and 7 beside the rollers 5, 5^b. As shown the roller 15^a is 20 mounted on a stud 15 (Fig. 2) attached to the gear 6 beside the stud 6^a, roller 15^a lying close beside and partially overlapping the roller 5^a, and between the opposed faces of the gear 6 and roller 5^a. The guide roller 25 15^b is similarly mounted on a stud attached to the gear 7 beside the roller 5^b.

Just after the roller 5^a clears the shoe 4^a, after reversing the bed and while the roller 5^a is operating on the lower part of shoe 30 3^a to accelerate the reverse movement of the bed, the guard roller 15^a lightly engages or follows the curved guide 4^e. This roller 15^a and guide 4^e merely act as safety devices to keep the periphery of the roller 5^a in 35 proper contact with the shoe 3^a during the latter part of the reversal movement; and also to enable the bed movement to be started at any point during the reverse movement at which the bed might be when the machine 40 was stopped. Thus if the machine should be stopped during the last part of the reversing movement when roller 5^a (for example) is engaged with the lower part of shoe 3^a, the guard roller 15^a and coacting 45 guide 4^e would prevent the bed being moved inward so as to improperly separate the surface of the roller 5^a from the shoe 3^a. And so if, at such time, it should be desired to reverse the reversal movement of the bed, 50 then such guide roller 15^a engaging the surface 4^e would move the bed outward until the roller 5^a again enters the slot between the opposed shoes 3^a, 4^a and takes control of the reverse.

55 Both rollers 5^a, 15^a (or 5^b, 15^b) pass out between the lower end of the shoes 3^a (or 3^b) and curved portion of the shoe 4 (or 4^m) just after the segment 8^b meshes with the gear 10^b (or 9^b) so that there is no clash between the mechanisms for driving the bed on the uniform portion of its stroke, and the mechanism for reversing the same at the end thereof.

60 The roller 5^b and shoes 3^b, 4^b have the same functions and operate in the same man-

ner as the roller 5^a and shoes 3^a, 4^a above described, when the bed is being reversed at the end of its inward uniform movement or stroke, and the roller 15^b and guide 4^e have the same functions and operate in the same manner as roller 15^a and guide 4^e above described, when the bed is being reversed at the end of its inward uniform movement.

What we claim is:

1. In combination with a reciprocable bed; a member attached thereto having two closely adjacent oppositely inclined faces arranged at an angle of less than ninety degrees to the plane of movement of said bed, said inclined faces converging toward the center of the bed and inclining downwardly and outwardly away from the center of the bed; means for driving the body uniformly during portions of its strokes; and two similar alternately operating means each adapted to engage the related inclined face of said member and reverse the body while in engagement therewith.

2. In combination with a reciprocable bed; a reversing member secured to the bed having two oppositely inclined faces arranged at an angle of less than ninety degrees to the plane of movement of said bed, said inclined faces converging toward the center of the bed; and inclining downwardly and outwardly away from the center of the bed; means for uniformly moving the bed during portion of its strokes; and a pair of separated but similar rotatable members carrying means respectively adapted to alternately engage the related face of the said reversing member and reverse the bed, substantially as described.

3. In a machine of the character described, in combination, a reciprocable bed; a reversing member secured to said bed and having two oppositely inclined faces arranged at an angle of less than ninety degrees to the plane of movement of said bed, said inclined faces converging toward the center of the bed and inclining downwardly and outwardly away from the center of the bed; and separate rotating members each provided with means which engages the related face of said member during the reversing movement of the bed, said means being in engagement with the related face during the entire time that the bed is being stopped from going in one direction and started in the opposite direction and until the normal speed of the bed is reached.

4. In combination a frame provided with ways; a bed adapted to reciprocate on said ways; a member depending from the bed having two oppositely inclined faces arranged at an angle of less than ninety degrees to the plane of movement of said bed, said inclined faces converging toward the center of the bed and inclining downwardly and outwardly away from the center of the

bed; means for uniformly driving the bed on portions of its strokes; and separated rotatable gears each carrying a crank pin adapted to engage the related inclined face 5 of the said member and reverse the bed.

5. In a machine of the character described, in combination, a frame; a reciprocable bed; an angular member connected with the bed and having oppositely inclined faces 10 arranged at an angle of less than ninety degrees to the plane of movement of said bed, said inclined faces converging toward the center of the bed and inclining downwardly and outwardly away from the center of the 15 bed; a fixed member opposite each inclined face and forming therewith the walls of a reversing slot; and two similar means each having a part adapted to enter one of the slots and engage the inclined face therein 20 and stop and start the bed while in engagement therewith.

6. In a machine of the character described, in combination, a frame; a reciprocable bed; an angular member connected with 25 the bed and having oppositely inclined faces arranged at an angle of less than ninety degrees to the plane of movement of said bed, said inclined faces converging toward the center of the bed and inclining downwardly 30 and outwardly away from the center of the bed; a fixed member opposite each inclined face the space between such member and opposed face forming a reversing slot; and a pair of oppositely rotating members, each 35 provided with a crank having a part adapted to enter one of the slots and engage the inclined face therein and stop and start the bed while in engagement with such face, substantially as described.

40 7. In combination with a reciprocable body; a pair of closely adjacent shoes connected with said body and inclined at an angle of approximately ninety degrees to each other said shoes converging toward the 45 center of the bed and inclining downwardly and outwardly away from the center of the bed; with means for driving the body at uniform speed during part of its stroke and two rotary members at opposite sides of the uniform 50 driving means each provided with means respectively adapted to engage one of said shoes at the end of the related uniform movement of the bed and to slow down, stop, and reverse the movement of the bed while 55 in engagement with said shoes.

8. In combination with a reciprocable member; a pair of adjacent shoes connected with said member and inclined at an angle of approximately ninety degrees to each 60 other; a rack on the member; a pinion meshing with said rack; and gearing for rotating said pinion alternately in opposite directions to drive the bed at uniform speed during part of each stroke thereof; with two rotatable members at opposite sides of the bed 65

driving pinion provided with means respectively adapted to engage the related one of said shoes to slow down, stop, and reverse the movement of the bed at the end of its uniform movement in the direction of said 70 rotary member.

9. In combination with a reciprocable member; a pair of adjacent shoes connected with said member and inclined at an angle of less than forty-five degrees to said member and at an angle of approximately ninety degrees to each other; a rack on the member; a pinion meshing with said rack; and gearing for rotating said pinion alternately in opposite directions to drive the bed at uniform 75 speed during part of each stroke thereof; with two rotatable members at opposite sides of the bed driving pinion provided with means respectively adapted to engage the related one of said shoes to slow down, 80 stop, and reverse the movement of the bed at the end of its uniform movement in the direction of said rotary member.

10. Means for slowing down, stopping, and reversing the movement of a reciprocal 90 body such as the bed of a printing press, comprising a long shoe attached to the body and inclined at an angle to the path of movement of the body; a short shoe fixedly attached to said body opposite the upper 95 end of the first shoe and parallel therewith; a rotatable crank adapted to engage the slot between said opposed shoes to effect the reversal of the movement of the said body; and means to prevent disengagement of the 100 crank from the long shoe after it has cleared the short shoe.

11. Means for slowing down, stopping, and reversing the movement of a reciprocal 105 body such as the bed of a printing press comprising a long shoe attached to the body and inclined at an angle to the path of movement of the body; an opposed member fixedly attached to said body opposite said shoe; a short shoe attached to said member 110 opposite the upper end of the first shoe and parallel therewith, the said member having a curved face on the side opposite the shoe; and a rotatable crank adapted to engage the slot between said opposed shoes to effect the 115 reversal of the movement of the said body; and means coacting with said member to prevent disengagement of the crank from the longer shoe after it has cleared the short shoe. 120

12. In a reversing mechanism for reciprocal bodies such as the bed of a printing press; a shoe attached to the body and inclined to the path of movement of the body; an opposed member attached to the body 125 opposite said shoe and having a curved face opposite the shoe; rotatable crank means adapted to engage the said shoe to effect the reversal of the movement of the said body; and a guard means connected with said 130

crank means adapted to engage the curved face of said opposed member to prevent disengagement of the crank pin from the shoe during the reversal period.

5. 13. In a reversing mechanism; means for slowing down, stopping, and reversing the movement of a reciprocal body such as the bed of a printing press; comprising a long shoe attached to the body and inclined to the

10 path of movement of the body; an opposed member fixedly attached to the body opposite said shoe and having a curved face opposite the shoe; a short shoe attached to said member opposite the upper end of the first

15 shoe and parallel therewith; rotatable crank means adapted to engage the slot between said opposed shoes to effect the reversal of the movement of the said body; and a guard roller connected with said crank means

20 adapted to engage the curved face of said member to prevent disengagement of the crank pin from the longer shoe after the crank has cleared the short shoe.

14. In means for imparting reciprocatory

25 movements to bodies such as the bed of a printing press; the combination of a reciprocable body, a rack connected therewith; a pinion for driving said rack; a pair of oppositely moving segments; gearing for driving

30 said segments simultaneously; and means for alternately meshing said pinion with said segments, thereby alternately driving the body in opposite directions.

15. In means for imparting reciprocatory

35 movements to bodies such as the bed of a printing press; the combination of a reciprocable body, a rack connected therewith; a pinion for driving said rack; a pair of oppositely moving segments; gearing for driving

40 said segments simultaneously; and means for alternately meshing said pinion with said segments, thereby alternately driving the body in opposite directions; with means for reversing the movement of the bed at

45 each end of its uniform stroke and while the pinion is disengaged from both segments, substantially as described.

16. In combination a reciprocable body such as the bed of a printing press; a rack

50 on said body; a pinion meshing with said rack; a second pinion beside the first pinion and slightly smaller than the first pinion; a pair of intermeshing gears adjacent the second pinion; segments carried by said gears

55 and means for laterally shifting the pinions so as to cause the second pinion to alternately mesh with said segments.

17. In combination a reciprocable body such as the bed of a printing press; a rack

60 on said body; a pinion meshing with said rack; a second pinion beside the first pinion and slightly smaller than the first pinion; a pair of intermeshing gears adjacent the second pinion; segments carried by said gears

65 and means for laterally shifting the pinions

so as to cause the second pinion to alternately mesh with said segments.

18. Means for imparting reciprocatory movements to bodies, such as the bed of a printing press; comprising a rack attached to the body; a pinion meshing with said rack; a second pinion beside said first pinion; a yoke carrying said pinions; a pair of intermeshing gears adjacent the pinions; a segment carried by each gear; and means for oscillating the yoke so as to move the pinions into positions to be alternately meshed with said segments whereby the body is alternately moved in opposite directions.

19. Means for imparting reciprocatory

80 movements to the bed of a printing press; comprising a rack attached to the body; a pinion meshing with said rack; a second

75 pinion beside and smaller than said first pinion; a yoke carrying said pinions; a pair of intermeshing gears adjacent the pinions; a segment carried by each gear; and means

70 for oscillating the yoke so as to move the pinions to be alternately meshed with said

65 segments whereby the bed is alternately moved in opposite directions; with means

60 for reversing the movement of the bed at each end of its uniform movement and while the pinion is disengaged from both

55 segments, substantially as described.

20. In means for imparting reciprocatory

movements to bodies, such as the bed of a printing press; the combination of a reciprocable body, a rack connected therewith; a

100 pinion for driving said rack; a pair of oppositely moving segments; gearing for driving

95 said segments simultaneously; means for alternately meshing said pinion with said

90 segments, thereby alternately driving the

85 body in opposite directions; gears at opposite sides of the gears carrying said seg-

80 ments and having crank pins; and shoes

75 connected with the reciprocable body and inclined at an angle to the plane of move-

70 ment of the body and adapted to be engaged by said crank pins to reverse the movement

65 of the body during the time that the pinion

60 is out of mesh with both segments.

21. Means for imparting reciprocatory

115 movements to bodies, such as the bed of a printing press; comprising a rack attached to the body; a pinion meshing with said

110 rack; a second pinion beside said first pinion; a yoke carrying said pinions; a pair

105 of intermeshing gears adjacent the pinions; a segment carried by each gear, and means

100 for oscillating the yoke so as to move the pinions into position to be alternately

95 meshed with said segments to move the bed

90 alternately in opposite directions; shoes con-

85 nected with the reciprocable body and in-

80 clined at an angle to the plane of movement

75 of the body; and gears arranged at opposite

70 sides of and meshing with the gears carry-

65 ing the segments; and crank means on said

60 130

- gears adapted to engage said shoes and reverse the movement of the body during the time that the pinion is out of mesh with both segments.
- 5 22. Means for imparting reciprocatory movements to the bed of a printing press; comprising a rack attached to the bed; a pinion meshing with said rack; a second pinion beside and smaller than said first pinion; 10 a yoke carrying said pinions; a pair of intermeshing gears adjacent the pinions; a segment carried by each gear; and means for oscillating the yoke so as to move the pinions into position to be alternately meshed 15 with said segments to move the bed alternately in opposite directions; reversing gears arranged at opposite sides of and meshing with the gears carrying the segments; shoes connected with the bed and inclined at an angle of less than ninety degrees to the plane of movement thereof; and crank means on said reversing gears adapted to engage said shoes and reverse the movement of the bed during the time that the 20 pinion is out of mesh with both segments.
- 25 23. In combination with a reciprocable body, a member attached thereto having two oppositely inclined faces converging toward the body and arranged at an angle of less than 90 degrees to the plane of movement of said body; means for imparting uniform movements to the body in each direction; and means coöperating with an inclined face at each end of the uniform movement of the bed body to slow down, stop and start the body on its return movement, substantially as described.
24. Mechanism as set forth in claim 23, having said faces inclined at an angle of 45 degrees to the line of movement of the body, substantially as described.
25. In combination with a reciprocable body, a member attached thereto having two oppositely inclined faces converging toward the body and arranged at an angle of less than 90 degrees to the plane of movement of said body; means for imparting uniform movements to the body in each direction; and means coöperating with an inclined face at each end of the uniform movement of the bed body to slow down, stop and start the body on its return movement, substantially as described.
26. Mechanism as set forth in claim 25, having said faces inclined at an angle of 45 degrees to the line of movement of the body or surface of the bed.
- In testimony that we claim the foregoing as our own, we affix our signatures.
